George Hinrod and Charles G. Moulton of Chicago Ill.

Assignors to

George Hinrod,

Letters Patent No. 2436, Dated Sept. 25. 1864

Design for Stove Plates,

The Schedule referred to in these Letters Patent and making part of the same.

To all whom it may concern,

Be it known that we George Hinrod and Charles G. Moulton of the City of Chicago in the County of Cook and State of Illinois have originated and designed a new and useful Pattern to be cast upon Stoves, of which the following is a full description, and exact description reference being had to the accompanying drawing making part of this Specification.

The Pattern which we claim is shown in figures, of the drawing letter "A," and is an acorn attached by its stem to a portion of its twig, upon which twig are two leaves, one on each side of the stem partially covering the cup of the acorn, which pattern is to be cast upon the doors and legs of the stove in Alto-relievo, as shown in the drawing. - The pattern is not shown on the lower front doors of the stove but may be used thereon if desired. - That we claim as our invention and desire to secure by Letters Patent is

The Design or Pattern to be cast upon Stoves, herein set forth and shown

Witnessed,

{ John R. Brown
Henry King.
